BENJAMIN T. HAAGENSON, OF ASHTABULA, OHIO.

ICE-BREAKING MARINE VESSEL.

1,071,735.

Specification of Letters Patent.

Patented Sept. 2, 1913.

Application filed May 4, 1912. Serial No. 695,185.

To all whom it may concern:

Be it known that I, BENJAMIN T. HAAGENSON, a citizen of the United States, residing at Ashtabula, in the county of Ashtabula and State of Ohio, have invented a certain new and useful Improvement in Ice-Breaking Marine Vessels, of which the following is a full, clear, and exact description, reference being had to the accompanying drawings.

This invention relates to marine vessels, and especially to that class of vessels used in navigating ice-bound waters.

In waters where ice floes are present, the ice along the pressure line between respective ice floes piles up to a considerable thickness and forms what are known, nautically, as windrows. These windrows frequently assume such proportions that they stop the progress of a vessel and imprison it so securely that it is with considerable difficulty the vessel is released, the use of dynamite or ice tools having to be resorted to. Boats known as ice crushers have been especially designed to navigate under such conditions and have been more or less successful in accomplishing this end, but their peculiar design limits their usefulness to a considerable extent.

The zone of contact between the ice and the vessel extends only a little above and below the water line, the horizontal section of the hull of the vessel, in this region, being substantially wedge shaped. It is obvious therefore, that when the vessel, running on an even keel, rams into the ice with the power of its momentum behind it, the impact will be of considerable force and as a result the boat will be securely wedged within the ice, resulting in the difficulties already set forth. If however, the boat is rocking at the time it contacts with the ice, the line of contact will be continually changing, and the ice will be pushed aside and the wedging action and the locking of the vessel within the ice will be prevented.

The object of this invention is to provide means which may be readily applied to vessels of ordinary and approved design whereby the vessels may be caused to oscillate or rock for the purpose of permitting them to be run through ice bound waters without the danger of their becoming stuck or imprisoned within the ice.

It is a further object of my invention to make this means adjustable, whereby varied

degrees of oscillation may be easily and readily imparted to the vessel at will.

These and further objects I procure through the embodiments of my invention set forth in the claims annexed hereto and illustrated in the accompanying drawings forming a part hereof in which—

Figure 1 is a cross-sectional view of the hull of a vessel having an embodiment of my invention applied thereto; Fig. 2 is a partial side elevation of the hull of a vessel with a portion of the side plates broken away to show another embodiment of my invention; Fig. 3 is a sectional view taken on the line 3—3 of Fig. 2 and looking in the direction of the arrows; Fig. 4 is a transverse sectional view of the hull of a vessel with a modified form of my invention applied thereto, and Fig. 5 is a view, similar to Fig. 4 showing another modification of my invention.

I have shown in the drawings, more or less diagrammatically, various means for accomplishing the desired result and will describe them in the order in which they appear in the drawings.

In the embodiment of my invention shown in Fig. 1, I have employed two gyroscopes for imparting to the vessel an oscillatory movement, these gyroscopes being contained within the hull of the vessel, which I have designated A throughout the several views of the drawings, between the decks B and C. Each gyroscope D is composed generally of a rotor d, a shaft d', and a motor d² all of which are contained within a casing d³. The casing d³ is provided at its top and bottom with suitable posts or trunnions which are journaled in stationary journal blocks b and c, respectively, secured to the decks B and C of the vessel. Such ball and roller bearings as are deemed necessary to insure perfect ease of operation of the various parts of the gyroscope, are employed. The lower part of the casing d³ terminates in a worm gear d⁴ for a purpose which will hereinafter be described.

Situated upon the deck B of the vessel, between the gyroscopes D is a reversible engine E. The shaft e of this engine extends athwartship and has secured to each of its ends a worm e' which is adapted to mesh with the worm gear d⁴ upon the lower part of the casing d³ of each of the gyroscopes. The angular inclination of both worms is in the same direction and both worms are

of the same pitch, causing a similar precessional movement to be set up simultaneously in both gyroscopes when the engine is operated. This precessional movement of the gyroscopes causes them to impart to the vessel a reverse thrust on the opposite sides of its keel which results in an oscillating or rocking motion of the vessel. This may be accomplished by either running the engine continually in one direction, or by reversing it, and causing an alternate right and left hand partial rotation of the gyroscope casings.

In the form of my invention shown in Figs. 2 and 3 I employ but one gyroscope and mount it in brackets secured to the deck B and anchored to the deck C of the vessel with its spinning or rotating axis in a vertical position at about the center of the hull A of the vessel. The gyroscope is contained in the casing F, provided with trunnions which are mounted in the brackets b' in a manner that will permit the gyroscope to be swung in a plane coincident with the longitudinal axis or medial line of the vessel. The gyroscope casing F is caused to swing upon its trunnions by a mechanism designated G, consisting of a worm gear g journaled upon a stationary block g' and having connection with the gyroscope casing through an adjustable crank pin g² and a connecting rod f. The worm gear g is rotated by a worm h secured to the shaft h' of the engine H. By this construction it will be seen that through the operation of the engine the gyroscope will be caused to swing in a "fore and aft" direction and cause a precessional movement to be set up within the gyroscope. This precessional movement will produce a transverse thrust of the gyroscope which will be transferred to the vessel through the substantial brackets b' within which the trunnions of the gyroscope casing are mounted, causing the vessel to rock. As the degree of oscillation imparted to the vessel is dependent upon either the speed of the engine or the extent of the throw imparted to the gyroscope by the mechanism G, and since the speed of the engine can be varied and the position of the crank pin g² can be adjusted at the will of the operator, the angular movement of the boat may be kept under perfect control. In order to realize the maximum influence of a single gyroscope, I propose to locate it as near the center of oscillation as possible, and to swing its spinning axis at intervals corresponding to the natural periodicity of the vessel.

Fig. 4 shows a method of rocking a boat by forcing water which is contained in tanks located on opposite sides of the vessel from one of the tanks to the other. The tanks which I have designated I and I' are mounted upon the deck B of the vessel, and are

connected by a shallow conduit or passage way i communicating with each of the tanks near its bottom. I have shown a large compressed air reservoir J, mounted upon the deck C of the vessel and communicating with the water tanks I and I' through the pipe j and branches j' and j² respectively. The reservoir J receives its supply of compressed air from the air compressor K. Interposed between the pipe j and its branches j' and j² is a valve j³ which establishes communication between the pipe j and either of its branches j' and j², at the same time causing the other branch to be thrown into communication with the atmosphere. This valve is under the control of a mechanism designated L consisting of an arm l pivoted at its lower end to a stationary bracket (not shown) and bifurcated at its upper end to receive a pin at the end of the valve operating lever. The arm l is swung in either direction by the stem of a pendulum l' which is pivoted at l² to a stationary A-shaped frame l³. The arm l is provided near its lower end with a cross beam on which are mounted adjustable stops l⁴ for engagement with the stem of the pendulum.

The operation of this device is as follows: Assuming that the parts are in the position shown in Fig. 4, compressed air will flow from the reservoir J through the pipe j, the valve passageway and the branch j' to the tank I displacing the water within this tank and forcing it through the conduit i into the tank I' and causing the vessel to rock toward the right. Through the pendular action of the vessel the pendulum l' is caused to swing in the same direction, and in so doing engages a stop carried by the cross-beam of the arm l, throwing this arm to the right, and causing the valve j³ to be thrown in its alternate position. When in this position, the valve establishes communication between the air reservoir J and the water tank I' through the branch pipe j². Immediately the accumulating air pressure within this tank will force the water back through the conduit i into the former tank I and cause the boat to rock to that side. In response to this swinging action of the boat, the pendulum l' reverses its course and swings back against the left hand stop of the arm l causing the reversal of the valve and the repetition of the operation above set forth. By this means it will be seen that an automatic control is provided for shifting the weight of water from one side of the boat to the other, and the amount of oscillation can be varied by the adjustment of the stops l⁴ upon the cross beam of the arm l.

In the modification of my invention shown in Fig. 5 I employ an electrical motor driven car M mounted on a transverse curved track N which is supported above

the upper deck of a vessel by suitable truss-work. The car is provided with suitable reversing mechanism m which is controlled by push rods m' adapted to engage stops n on either end of the track N when the car reaches either of its extreme positions. The car carries a water tank n^2 in which any desired quantity of water may be placed necessary to impart to the vessel, through its weight, the desired degree of oscillation when it travels to either end of its track. A current may be supplied to the motor m^3 through any suitable means as by the wires O and the rails n' of the track.

Having thus described my invention, what I claim is:

1. The combination, with a marine vessel, of controllable means operating on opposite sides of the keel or medial line for imparting a rocking or oscillating movement to said vessel, and mechanism whereby said means is caused to reverse the direction of its action upon the vessel at regular and predetermined intervals of time.
2. The combination, with a marine vessel, of a gyroscope, and means for moving its spinning axis in a substantially fixed plane with respect to the vessel and at intervals corresponding to the periodicity thereof.
3. The combination, with a marine vessel, of a plurality of gyroscopes and means, independent of the action of the vessel, for moving their spinning axes in a substantially fixed plane with respect to the vessel and at intervals corresponding to the periodicity thereof.
4. The combination, with a marine vessel,

of a gyroscope located within the hull of the vessel, a casing within which the gyroscope is capable of spinning and having trunnions extending from its sides the axis of which is at right angles to the spinning axis of the gyroscope, a bracket located on each side of the longitudinal center line of the vessel within which is journaled one of the trunnions of the gyroscope casing, and mechanism for rocking the gyroscope casing upon its trunnions.

5. The combination, with a marine vessel, of a gyroscope having its spinning axis coincident with the vertical center line of the vessel, a casing for the gyroscope having trunnions projecting from its sides at right angles to the spinning axis of the gyroscope and extending transverse the vessel and mounted within brackets, and mechanism for swinging the spinning axis of the gyroscope a varied number of degrees each side of its vertical position.

6. The combination, with a marine vessel, of a gyroscope, supporting means for said gyroscope which permits a forward and rearward movement of the spinning axis thereof in a fixed plane with respect to the vessel, and means for imparting to the axis of the gyroscope, movement at intervals corresponding to the periodicity of the vessel.

In testimony whereof, I hereunto affix my signature in the presence of two witnesses.

BENJAMIN T. HAAGENSON.
